UNITED STATES PATENT OFFICE.

ANDREW NOBLE, OF NEWCASTLE-UPON-TYNE, ENGLAND, ASSIGNOR TO W. G. ARMSTRONG, MITCHELL & CO., (LIMITED,) OF SAME PLACE.

FUSE FOR PROJECTILES.

SPECIFICATION forming part of Letters Patent No. 372,814, dated November 8, 1887.

Application filed May 10, 1887. Serial No. 237,736. (No model.) Patented in England February 6, 1885, No. 1,673, and in Italy December 31, 1885, No. 19,133.

To all whom it may concern:

Be it known that I, ANDREW NOBLE, late captain in the Royal Artillery, of Jesmonddene House, Newcastle-upon-Tyne, England, manufacturing engineer, a subject of the Queen of Great Britain, have invented certain new and useful Improvements in Fuses for Projectiles, (for which I have received Letters Patent in Great Britain, dated February 6, 1885, No. 1,673, and in Italy, dated December 31, 1885, No. 19,133,) of which the following is a specification.

This invention has for its object improvements in fuses for projectiles.

The fuses to which this invention relates are armed or rendered sensitive by the movement of a bolt or locking part, caused by the rotary motion of the projectile imparted by the rifle-grooves of the gun. The explosion takes place on impact, a pellet of fulminating material then coming into contact with a cone or point by which the explosion is determined. Such fuses may take different forms. Various examples are shown in the drawings hereunto annexed.

Figure 1 is a longitudinal section of one form of the fuse, in which the fulminating material is carried by the movable weight. Fig. 2 is a modification of the same fuse, in which the point or anvil is carried by the weight. Fig. 3 is an end view of another modification of the fuse, adapted to be screwed into the base of a projectile. Fig. 4 is a section of the fuse on the line A B, and Fig. 5 a section on the line C D. In this fuse two actions are required to render it sensitive, first, the pressure of the powder-gases in the gun when fired, and then the rotation of the projectile in the gun. Figs. 6 and 7 show longitudinal sections, and Fig. 8 a transverse section, of another modification of the fuse. This modification is so contrived as to insure that it shall not become sensitive until the projectile has left the gun. Fig. 6 is a section on the line B B, Fig. 8. Fig. 7 is a section on the line A A, and Fig. 8 a section through the line D D, Fig. 7. Figs. 9, 10, and 11 show the fuse combined with time-fuse mechanism. Fig. 9

is a section through the line B B, Fig. 10. Fig. 10 is a transverse section through the line C C, Fig. 11; and Fig. 11 is a section through the line A A, Fig. 10.

In Fig. 1, which shows a fuse to be inserted into the nose of a projectile, Z is a cylindrical main chamber forming the outer body or casing and having around a portion of its exterior a screw-thread to allow of its being screwed into a hole formed to receive it in the nose of the projectile. It contains within it a small cylindrical weight, A, capable of movement within the interior of the chamber, which is of corresponding form. There is a passage, A', bored through this cylindrical weight axially, and in this passage the fulminating-pellet B is lodged. The movement of the weight within the main chamber is prevented, until the time of firing, by means of a locking part, which, as shown, is formed by a small bolt, C, capable of moving radially in a side chamber or passage, C', formed to contain it at the fore end of the main chamber, and this bolt itself is locked by a split pin, D, inserted into a hole parallel to the axis of the fuse and of the projectile, and there retained by a small transverse wire, E. All endwise movement of the weight A before the projectile carrying the fuse is fired, is prevented by a ring, A'', of lead or other compressible material, carried at its rear end, being pressed against by a perforated screw-plug, G, which closes the rear end of the fuse.

The action of the fuse then is as follows: When the projectile is started rapidly into movement by the pressure of the powder-gas behind it, the inertia of the split pin D causes the retaining-wire E to be shorn or cut through. The pin D then passes to the rear end of the hole, in which it is lodged, and thence becomes jammed and held out of the way. The bolt C is now free, and as soon as the projectile receives the rotation which the rifle-grooves in the gun are designed to impart to it the bolt moves outward or away from the axis of the fuse by centrifugal action, thereby freeing the small cylindrical weight A, while the locking part occupies the side passage, C'. When the

projectile, after leaving the gun, encounters an obstacle and its forward movement is checked, the cylindrical weight A continues its course and passes to the front end of its chamber. The pellet B of fulminating material is thus brought into contact with a cone or point, F, fixed in the end of the chamber, and the explosion ensues.

In the modified arrangement shown by Fig. 10, the cylindrical weight A is made to carry the cone or point F for firing the fulminating pellet B, and this pellet is lodged in a cavity in a screw-plug, H, made to screw into the front end of the cylindrical chamber. This arrangement admits of the screw-plug, carrying the pellet or detonator B, being readily removed from the fuse, and replaced when circumstances may render this advisable. In other respects the fuse is constructed in the 20 way described with reference to Fig. 1.

In the fuse shown at Figs. 3, 4, and 5, which is adapted to be screwed into the base of a projectile, the cylindrical weight and centrifugal locking-bolt have to be released by the action 25 of the powder-gases. The fuse has a cylindrical cavity, I, in its rear face, which is closed by a disk, J, and this is supported in its place by a leaden ring, K. Two screws, L, are inserted into the disk, and their heads overlap 30 the fore end of the cylindrical weight A and prevent it from moving forward. The radial bolt C also is kept in place to dog the weight against forward movement by a double pin or staple, M, parallel to the axis of the fuse, and 35 held down in its place either by a coiled spring, N, as shown, or by a pillar of soft metal.

When the gun is fired, the powder-gas acts against the movable disk J in the base of the fuse, and, crushing the leaden ring K, by which 40 it is retained, drives it forward so far as to carry the heads of the screws L clear of the end of the cylindrical weight A and allow it freedom to move. At the same time the disk J comes against the rear end of the double 45 pin or staple M and lifts it out of the way of the radial bolt, compressing the spiral spring N, or crushing the piece of soft metal which opposes the movement of the staple. Then, as before, as soon as the projectile takes up 50 the rotary motion which the grooves in the gun impart to it, the bolt C moves outward, leaving the cylindrical weight A entirely free.

When the forward movement of the projectile is checked by impact with any obstacle, 55 the weight A moves forward, bringing the fulminating-pellet B into contact with the cone or point F, provided to fire it. The flash passes forward through perforations in the screw-plug O, which closes the front end of the fuse, 60 and which carries the cone or point F, and the main charge contained within the body of the shell is ignited.

In the modification of the fuse shown at 65 Figs. 6, 7, and 8 the release of the cylindrical weight is so contrived as to insure that it shall

not take place before the projectile has left the gun. The fuse shown is adapted to be screwed into the nose of a projectile.

Between the fore end of the weight A and the front of the chamber within which it moves 70 the locking part, formed in this instance by a hard-metal ball, P, instead of the bolt before described, is provided, and this ball is held in its place by a ring or outer cylinder, Q, surrounding the weight and projecting from its 75 fore end. A notch is cut in the ring, and in this notch the ball P is lodged. A projection from the weight also enters this notch and rests against the ball. The outer cylinder or ring, Q, is prevented from moving along the 80 weight A until the gun is fired, by a copper cap, R, which is placed on the fore end of the weight A, and which has outwardly-projecting flanges supporting the rear end of the ring Q. A stud, Q', projecting from the side of the 85 ring enters a groove in the side of the cylindrical chamber and prevents the ring from turning. When the gun is fired, the flanges on the copper cap are insufficient to retain the ring Q in its place, and its inertia causes it to 90 fall to the rear. The metal sphere P, which the ring previously retained, now finds itself entering the side passage, X, formed between flat surfaces and constituting a spiral or snail-like enlargement at the fore end of the cylindrical chamber. At the instant when it is released 95 the ball P is resting against the side or wall of the chamber, where it approaches most nearly to the center or axis of the fuse. When the projectile commences to revolve, this ball 100 rolls along the walls of the chamber outwardly away from the center until, finally, when it has made about three-fourths of a revolution, it drops down into a small pocket, S, provided for it at the extremity of the side passage, X, 105 where it is retained out of the way. Then, as in the previous case, the cylindrical weight A, being entirely free, it moves forward in its chamber as soon as the velocity of the projectile is checked by impact. The fulminating- 110 pellet B then comes into contact with the cone or point F, provided to effect its discharge. It explodes and the flash passes back, as in the fuses previously described, to the main charge 115 within the shell.

In the modification shown at Figs. 9, 10, and 11, in which the percussion-fuse is combined with time-fuse mechanism, the parts of the percussion-fuse are constructed in the same manner as in Figs. 6, 7, and 8, and marked 120 with the same letters of reference, while the time mechanism is of ordinary construction.

Having now particularly described and ascertained the nature of my said invention and in what manner the same is to be performed, 125 I declare that what I claim is—

In a fuse for projectiles, the combination of the body of the fuse having the main chamber or cavity, the weight within said chamber and movable lengthwise thereof, the side pas- 130

sage communicating with the fore end of the main chamber, and the locking part normally retained in position against the fore end of the weight for dogging it against forward movement, and by the movement outwardly, by way of the side passage, imparted to said locking part by the rotation of the projectile, the weight is left free to advance within the cham-

ber of the fuse, substantially as and for the purpose set forth.

A. NOBLE.
